UNITED STATES PATENT OFFICE.

RICHARD ERNST, OF NEW YORK, N. Y.

HAIR-DYE.

1,108,157.

Specification of Letters Patent. Patented Aug. 25, 1914.

No Drawing.

Application filed September 23, 1913. Serial No. 791,332.

To all whom it may concern:

Be it known that I, RICHARD ERNST, a citizen of the United States, and resident of New York, in the county of New York and State of New York, have invented certain new and useful Improvements in Hair-Dyes, of which the following is a specification.

The object of this invention is to produce a hair dye in a powder form, simple in application, and of non-poisonous and non-irritating ingredients. In making this hair dye let us take for example one ounce of this powder, which is enough for one application. This contains two drams of burnt sugar, two drams of logwood, and four drams of pyrogallol. The above mentioned proportions may vary according to the shade desired. For a light shade the pyrogallol is decreased, and the logwood and burnt sugar increased, whereas for a dark shade the pyrogallol is increased, and the logwood and burnt sugar decreased.

The powder when used is mixed with water until it becomes a creamy substance, which is then applied to the hair by means of a brush and subsequent combing.

Claim.

1. A hair dye substantially as described, having the combination of burnt sugar, pyrogallol, and logwood. 30
2. A hair dye substantially as described, having a combination of burnt sugar, pyrogallol, and logwood in a powder form adapted to form a creamy mixture on the addition of water. 35

Signed at New York city, in the county of New York and State of New York, this 21st day of August, A. D. 1913.

RICHARD ERNST.
